TABLE LAMP BASE

Thomas F. Roche, 21 W. Main St.,
Merrimac, Mass. 01860

Filed Sept. 26, 1968, Ser. No. 13,731

Term of patent 14 years

Int. Cl. D26—02

U.S. Cl. D48—20

FIG. 1

FIG. 2

FIG. 3

FIG. 1 is a front view of my new design.

FIG. 2 is a right side view of my new design.

FIG. 3 is a left side view of my new design.

The dominant features of my design reside in the portions shown in full lines. The bulb and lamp shade are shown in broken lines for illustrative purposes only.

I claim:

The ornamental design for a table lamp base, as shown and described.
